INVENTOR:
August Westman
BY
Hugh H. Wagner,
ATTORNEY

UNITED STATES PATENT OFFICE.

AUGUST WESTMAN, OF QUINCY, ILLINOIS, ASSIGNOR OF ONE-HALF TO EDWARD A. WESTMAN, OF ST. LOUIS, MISSOURI.

POULTRY-HOVER.

1,385,235.

Specification of Letters Patent. Patented July 19, 1921.

Application filed November 6, 1920. Serial No. 422,162.

To all whom it may concern:

Be it known that I, AUGUST WESTMAN, a citizen of the United States, residing at the city of Quincy, in the county of Adams and 5 State of Illinois, have invented certain new and useful Improvements in Poultry-Hovers, of which the following is a specification.

This invention relates particularly to the means for controlling the amount of oil or 10 the like fed to the burner or lamp in a poultry hover.

In the accompanying drawings forming part of this specification, in which like numbers of reference denote like parts wherever 15 they occur,

Figure 1 is a side elevation;

Fig. 2 is a vertical sectional view through the burner and supply pipes, taken on the line 2—2 in Fig. 3; and

20 Fig. 3 is an elevational view at a right angle to Fig. 2.

The burner 1 receives its fuel from reservoir 2 through pipes 3, 4, 5, and 6. Pipe 3 and pipe-joint 7 are located in the hollow 25 formed within casting 8.

Rod 9 passes through casting 8 and is controlled by lever 10 at that end thereof. At its other end, rod 9 passes through an opening through bracket 11.

30 Arm 12 is fixed to that end of rod 9, and at the other end of link 12 the said link is pivoted at 13 to link 14, which is pivoted at 15 to burner 1.

An elongated aperture 16 in pipe 6 is the 35 port for the admission of oil from pipe 5 into pipe 6 and thence to burner 1. This aperture 16 opens into chamber 17 in pipe-union 18. Burner 1 can be raised so high by rotation anti-clockwise of lever 10 that 40 all of aperture 16 will be closed by the stub of union 18, the mouth of the opening through which is closed by cap 20 and gasket 21.

Rotation clockwise of lever 10 causes arm 45 12 to pull on link 14 and thereby to cause the descent of burner 1 and with it of pipe 6, which results in opening aperture 16 or enlarging the opening thereof into chamber 17, with a consequent increase of flow of oil to 50 the burner 1.

The advantages of this construction are a positive and reliable control of the feed of oil to the burner 1 to maintain reliably the heat or temperature within hover 22 for the 55 preservation of the life of the chicks har-

bored therein. In hovers now known, nothing is provided for this regulation, and when the reservoir 2 and the oil contained therein become cold the flow of oil through pipe 3 and to the burner 1 decreases and 60 sometimes stops altogether, the result in either instance is danger or death to the chicks under hover 22.

The connection between pipe 5 and union 18 is threaded at 23, and the connection between pipe 6 and union 18 is one by which pipe 6 is slidable through cap 20 and stub 19.

Bracket 11 is preferably formed integral with union 18, but may be otherwise fixed thereto.

70 One advantage of this construction is that lever 10 or analogous part is located outside of hover 22, which makes it conveniently accessible. A further advantage is that it is located near oil-reservoir 2.

75 Having thus described this invention, I hereby reserve the benefit of all changes in form, arrangement, order, or use of parts, as it is evident that many minor changes may be made therein without departing from the 80 spirit of this invention or the scope of the following claims.

I claim:

1. A heating apparatus for poultry hovers comprising a movable fuel burner, a fuel 85 inlet pipe carried by the burner and provided with inlet ports, hollow means connecting the inlet pipe with a source of fuel supply and forming a valve chamber, and means engaging the fuel burner for moving 90 the same as a unit whereby to adjust the position of the ports in the inlet pipe with respect to the chamber to regulate the flow of fuel to the burner.

2. A heating apparatus for poultry hovers 95 comprising a movable fuel burner, a fuel inlet pipe carried by the burner and provided with opposed inlet ports, hollow means connecting the inlet pipe with a source of fuel supply and forming a receiving chamber, said inlet pipe being mounted for movement within the chamber, and manually operable means engaging the fuel burner for moving the same as a unit whereby to actuate the fuel inlet pipe to adjust the 100 position of the inlet ports therein with respect to the chamber to regulate the flow of fuel to the burner.

3. In a heating apparatus for poultry 105 hovers including a movable fuel burner and 110

a fuel storage tank, an inlet pipe provided with inlet ports connected with the burner, a fuel supply pipe connected with the storage tank, a casing fixed to the service pipe and embracing the inlet pipe, said inlet pipe being movable with respect to the casing whereby to open or completely or partially cut off communication of the inlet ports with respect to the interior of the casing, and 10 means pivotally connected with the casing and engaging the fuel burner whereby to move the same for the purpose set forth.

4. In a poultry hover, means outside the hover proper for controlling the amount of 15 oil supplied to the burner within the hover, the said means consisting in a pipe connected with the burner and having a port therein, a member containing a chamber in which the said pipe is adapted to slide to 20 open or enlarge or close the passage through the said port, a link so attached as to be adapted to slide the said pipe, an arm

adapted to actuate the said link, and a rod connected to the said arm and extending from the said arm within the hover proper 25 to a point outside the same.

5. In a poultry hover, means outside the hover proper for controlling the amount of oil supplied to the burner within the hover, the said means consisting in a pipe connected with the burner and having a port 30 therein, a member containing a chamber in which the said pipe is adapted to slide to open or enlarge or close the passage through the said port, a link so attached as to be 35 adapted to slide the said pipe, an arm adapted to actuate the said link, a rod connected to the said arm and extending from the said arm within the hover proper to a point outside the same, and means for rotating the 40 said rod.

In testimony whereof I hereunto affix my signature.

AUGUST WESTMAN.
